UNITED STATES PATENT OFFICE.

GEORGE W. RUSSELL, OF WARREN, OHIO, ASSIGNOR, BY MESNE ASSIGNMENTS, TO THE AETNA-STANDARD ENGINEERING COMPANY, OF WARREN, OHIO, A CORPORATION OF OHIO.

STRAIGHTENING MACHINE.

Application filed October 22, 1925. Serial No. 64,071.

This invention relates to straightening machines, and particularly to the arrangement of the gearing therein so that adjustments of the machine may be made without disturbing the gear connections and causing faulty operation of the machine.

Sheet straightening machines of the roll type as heretofore made have comprised an upper and a lower set of rolls, one of these sets being adjustable with respect to the other, and all of the rolls being driven. In some machines the rolls are driven through wobblers or universal couplings, but this construction does not stand up under heavy work and is quite expensive. In other forms of straightening machines the gears of the upper set of rolls have been connected to the lower set, but upon adjustment of the upper set of rolls away from the lower set the back lash of the gears frequently becomes so great that the sheets are marked. It has also been proposed to drive the lower rolls and to operate the upper rolls frictionally, but these machines have not proved satisfactory. It has also been attempted to use a chain drive between the end rollers of the upper set and the opposite end rollers of the lower set. The chain, however, allows back lash and is no better than the ordinary gear connected machine.

I provide a driving gear which is substantially stationary and a meshing gear which is movable with the adjusting rolls and arranged to drive the same, the line connecting the centers of the driving gear and the meshing gear being substantially perpendicular to the direction of adjustment. By reason of this arrangement the center to center distance of the gears is practically unchanged upon adjustment of the rolls and consequently there is no excessive back lash at any time. The machine, therefore, operates smoothly for all adjustments and the tendency to mark the sheets is done away with.

In the accompanying drawings, illustrating one embodiment of the invention—

Figure 1 is an end elevation of a gear straightening machine embodying the invention;

Figure 2 is a top plan view of the machine;

Figure 3 is a side elevation, and

Figure 4 is a section on the line IV—IV of Figure 1.

In the illustrated embodiment of the invention, there is shown a straightening machine comprising a lower roll frame, indicated generally by the reference character 2, and carrying straightening rolls 3, and an upper frame, indicated generally by the reference character 4, and carrying upper straightening rolls 5.

The upper frame 4 is adjustable relative to the lower frame 2. Hand wheels 6 are provided for making such adjustment. These hand wheels are mounted on shafts 7 having worms 8 engaging worm wheels 9. The worm wheels 9 are keyed to screw shafts 10 which are threaded into nuts 11 in the upper frame 4. Springs 12 tend to hold the frames apart, but the adjustment of the hand wheels 6 provides positive means for adjusting the upper frame relative to the lower frame and preventing spreading thereof during operation of the machine. A separate hand wheel 6 is provided at either end of the machine so that the upper frame can be tilted relative to the lower frame, as indicated in Figure 3. This arrangement makes it possible to set the rolls as shown in the drawings so that the sheet is deflected or corrugated transversely to its line of movement, thus breaking up any permanent bends in the sheet and straightening it. The rolls at the delivery end are spaced further apart and serve to deliver the sheet flat. In the machine shown there are eight lower rolls and nine upper rolls, and these are connected in sets by gears 13, all of which are mounted in housings 14 at one end of the machine.

The driving mechanism is at the opposite end of the machine from the gears 13. Power is supplied by a motor 15 mounted on a bracket 16 and connected to a jack shaft 17 through gearing 18. The jack shaft is carried in bearings 19 mounted on the bracket 16 and has keyed thereto an overhanging pinion 20. The pinion 20 meshes with a gear 21, which in turn meshes with gears 22. The gears 22 are connected to rollers 3 in the lower set and drive the connected sets of lower rolls at either end of the machine. The middle set of lower rolls is driven from the

gear 21 through a shaft 23 which is connected to one of the gears 13. The gears 21 and 22 are fixed relative to the pinion 20 and an adjustment of the machine does not disturb the 5. connections.

The upper set of rolls is driven through a gear 24 which meshes with the pinion 20. Referring particularly to Figure 4, it will be seen that a straight line connecting the centers of the pinion 20 and gear 24 is practically horizontal, that is to say, it is substantially perpendicular to the direction of adjustment of the upper frame 4. Both the pinion 20 and the gear 24 are made considerably wider than the adjacent gears so that they can mesh with one another without interference. This is clearly shown in Figure 2 of the drawings. The gear 24 is connected to one of the rolls in the middle set of upper 10 rolls so that all of them are driven through the gears 13 in this particular set. The two sets of upper rolls lying at the end of the machine are driven through gears 25 which mesh with the gear 24 and are mounted on 15 shafts 26, these shafts carrying one of the gears 13 in the end sets.

An adjustment of the upper frame with respect to the lower frame will not materially alter the center to center distance 20 of the pinion 20 and the gear 24 because of their position relative to one another with respect to the direction of adjustment. The doing away of the spreading of the gears on adjustment of the upper frame prevents 25 back lash and does away with the marking of the sheets which frequently occurred with machines of the old type. Also, the life of the machine is materially increased since the gears operate in the way they are designed 30 to work and never have to carry the load on the tips of the teeth as is frequently necessary in the old style machines.

While I have shown and described a preferred embodiment of my invention, it will 35 be understood that I am not limited to its preferred embodiment, as the invention may be otherwise embodied within the scope of the following claims.

I claim:

1. A sheet straightening machine, comprising an adjustable frame extending in the direction of travel of the sheet through the machine, straightening means mounted on the frame and adjustable therewith, a gear mounted on the frame and adapted to drive 55 the straightening means, a substantially stationary driving gear meshing with the first mentioned gear, and independent adjusting means at each end of the frame for adjusting its position, the gears being between the adjusting means and having their centers located in a line generally perpendicular to the direction of adjustment, whereby the spreading of the gears is substantially a minimum for any adjustment of the frame, 60 substantially as described.

2. A sheet straightening machine comprising a pair of relatively movable frames, a plurality of rolls in each frame, gearing for each frame connecting the rolls thereof together, and a gear on one frame making a driving connection with a gear on the other frame, the line connecting the centers of said gears being at an angle approaching a right angle to the direction of relative movement of the frames, substantially as described.

3. A sheet straightening machine comprising a pair of relatively movable frames, means arranged adjacent the ends of the frames for effecting adjustment thereof, a plurality of rolls in one of said frames, gearing carried by said frame connecting the rolls thereof together, and a gear mounted on the other frame and making a driving 85 connection with a gear on the first mentioned frame, the line connecting the centers of said gears being at an angle approaching a right angle to the direction of relative movement of the frames, the point of engagement of said gears lying intermediate the ends of the frame, substantially as described.

In testimony whereof I have hereunto set my hand.

GEORGE W. RUSSELL.
